UNITED STATES PATENT OFFICE.

EUGENE T. KIEFFER AND WILLIAM B. STEVENSON, OF PHILADELPHIA, PENNSYLVANIA, ASSIGNEES TO VICTOR TALKING MACHINE COMPANY, A CORPORATION OF NEW JERSEY.

TALKING-MACHINE CABINET.

Application filed October 23, 1922. Serial No. 596,201.

To all whom it may concern:

Be it known that we, EUGENE T. KIEFFER and WILLIAM B. STEVENSON, both citizens of the United States, and residents of the city of Philadelphia, county of Philadelphia, and State of Pennsylvania, have invented certain new and useful Improvements in Talking-Machine Cabinets, of which the following is a specification.

- 10 Our invention relates to cabinets for talking machines and particularly to those cabinets wherein the entire mechanism for reproducing sound and the devices for amplifying the reproduced sound are contained
- 15 within the confines of the cabinet structure, when the cabinet is closed, and wherein a lid or cover is raised, elevated or moved to give access to the turntable and sound box when it is desired to operate the machine.
- 20 In talking machines of the enclosed horn or cabined type, the relatively heavy parts of the mechanism, e. g. the motor, turntable and horn supporting bracket, are all usually mounted within and are carried by the
- 25 upper part or top of the main cabinet structure, space being ordinarily provided below or on one or both sides of the said mechanism for the storage of talking machine records.
- 30 The cabinet work in the lower parts of the cabinets for such talking machines is generally of such a kind as to necessarily afford ample strength and rigidity. It is comparatively easy to make the lower parts 35 of such cabinets strong enough to withstand all the rough usage to which they may be subjected.
- 36 During their transportation or shipment from factory to distributor, talking machines are subjected to relatively rough or severe handling, and it has been found necessary to brace, stiffen and reinforce the whole cabinet, with a built-in partition generally located near the top of the cabinet 45 wherein are mounted the heavy motor and horn bracket. Such a partition, however, permanently separates the part of the talking machine cabinet which is above the motor-board from that below the motor-board,
- notwithstanding the fact that such rigid 60 permanent immovable partition has been usually provided with a rectangular opening into which is loosely fitted the usual motor-board.
- 55 But the motor-board, in such constructions, forms substantially no part of the talking machine cabinet; that is to say, the strength of the cabinet would be not substantially affected by the presence or absence of the motor-board per se. The heavy built- 60 in partition of itself is relied upon to impart to the cabinet structure the requisite strength and rigidity. The said built-in partition could not be removed without destroying the cabinet structure, with the result that the space below this partition was almost inaccessible for the purpose of wiring for the motor, or of mounting the horn or removing it or adjusting it, as might become necessary, except through the relatively small opening provided therein for the reception of the motor-board. For this reason therefore, it has also been the usual practice to provide, in the rear or back vertical wall of the cabinet a relatively large opening or passage to give ample access to the space immediately below the heavy built-in partition, such opening being normally 75 closed by a panel, removable board or door. This large opening in the rear wall, however, made it necessary to make the heavy built-in partition even heavier and stiffer, to compensate to some degree for the corresponding weakening of the rear wall, and the consequent weakening of the cabinet 80 structure.
- 85 From the above it will now be also plain that the cabinets referred to above as the ordinary talking machine cabinets, were in a sense, complete casings or housings, in 90 themselves made strong enough to successfully resist the hard usage to which they are subjected, and the motor mechanism is another complete mechanism adapted to be housed or contained within the cabinet, and 95 protected therein by the cabinet.
- The objects of the present invention are to provide a talking machine cabinet con-

struction wherein the motor-board itself, when positioned within the cabinet, strengthens, reenforces and stiffens, and substantially forms a part of the cabinet structure, obviating the necessity of providing a built-in, immovable, wall or partition in order to make the cabinet sufficiently strong to withstand severe handling; to so mount a removable partition in the cabinet of a talking machine that the four edges thereof tightly substantially abut against the four vertical walls of the cabinet, and impart rigidity to the whole cabinet; to provide a construction wherein the closure for the top of the cabinet, upon which are mounted the swinging arm, the horn and the motor, is readily removable from the talking machine cabinet to give free access to the portion of the cabinet normally below said partition; to make the motor-board and the horn-board together substantially as large as the interior of the top of the talking machine cabinet.

Further objects of our invention are to provide the interior side walls adjacent the top of the cabinet with metallic strips along the opposite top side edges of the cabinet to strengthen the cabinet and to form built-in supports for the horn-board and the motor-board; to so mount such strips in the walls of the cabinet that they substantially rest on the tops of said walls, and the weight of the parts supported on said strips is transmitted to the walls of the cabinet vertically as distinguished from being transmitted thereto by brackets merely fastened to the inside faces of said walls; to so support the motor-board and the horn-board that they may be lifted out of said cabinet without scratching the inner surfaces of the side walls; to provide a cabinet structure with metallic bars of such a shape as to cooperate with the side walls and with the motor-board and the horn-board, to strengthen the whole talking machine cabinet; and to provide a partition within a talking machine cabinet, which consists of two parts, a motor-board and a horn-board, either of which is removable from the cabinet without displacing or removing the other, and one of which may be operative to hold one side or edge of the other board firmly against the support for said boards.

Other objects of our invention will appear in the specification and claims below.

Referring now to the drawings forming a part of this specification, and in which the same reference characters are employed throughout the various views to designate the same parts, Fig. 1 is a plan view of a talking machine cabinet with the lid removed, and showing the motor-board, the horn-board, the swinging arm, the horn, the turntable, and the motor of a talking ma-

chine, and our invention as applied thereto. 65

Fig. 2 is a vertical longitudinal sectional view of the top portion of a talking machine cabinet shown in Fig. 1, showing the positions of the motor-board and the horn-board with respect to the cabinet and the parts cooperating therewith. 70

Fig. 3 is a perspective view of one of our Z-bar supports for the motor-board and horn-board of a talking machine and Fig. 4 is a similar view of the other Z-bar support. 75

Fig. 5 is a vertical section on the line 5-5 of Fig. 1; and

Fig. 6 is a vertical sectional view of a portion of the cabinet shown in Fig. 1 and taken on the line 6-6. 80

A talking machine cabinet, as usually constructed, consists of four vertical walls comprising the front wall 1, the rear wall 2 and two opposite side walls 3 and 4 respectively, all disposed generally vertically and generally enclosing a substantially rectangular space. These vertical walls may be paneled in the usual manner and, as usual, the top portions of the vertical side walls 90 may be made of separate strips 5, 6, 7 and 8, of molding, rigidly and permanently secured to the main portions of the walls 1, 2, 3 and 4 by glue and suitable dowel pins 9, said dowel pins being blind from the top 95 of said strips and extending vertically down into the main portions of the vertical walls 1, 2, 3 and 4. It has been heretofore usual to fit or build into the cabinet work of the four walls 1, 2, 3 and 4 of the cabinet a heavy partition completely filling the space below the line where the strips 5, 6, 7 and 8 join the tops of the main portions of the walls 1, 2, 3, and 4, and to provide such rigid partition with a rectangular 100 opening therein into which loosely fits a motor-board with the motor depending therebelow. In such construction the motor-board is secured to the horizontal partition 105 in the top of the cabinet structure. 110

Such construction is, however, replaced by our invention as follows: In the inner faces of two opposite walls of the cabinet structure as, for instance, in the inner face of the side walls 3 and 4, and preferably 115 where the strips 7 and 8 respectively engage the top edges of the main portions of the side walls 3 and 4, we provide longitudinal grooves 10 and 11 extending preferably the length of each side wall from the front to the rear of the inner face thereof, the grooves in the opposite side walls being parallel and in the same horizontal plane. These grooves or recesses are preferably 120 made along the inner edges of the inside faces of said strips 7 and 8, and where the openings are provided in said strips for the reception of the dowel pins 9, we prefer- 125

ably extend said grooves 10 and 11 laterally outwardly towards the outside wall of said strips to form recesses 12 and 13 respectively therein.

- 5 These grooves are for the purposes of receiving respectively the horizontal flanges 14 and 14' of a pair of metallic bars or angle-irons 15 and 15' substantially Z-shaped in transverse cross-section, provided 70
- 10 respectively with vertical connecting webs 16 and 16' and with relatively horizontal lower flanges 17 and 17' extending from the lower edges of said webs 16 and 16' respectively. The upper flanges 14 and 14' of 75
- 15 the Z-bars 15 and 15' are preferably respectively provided with extensions or ears 18 and 18' disposed in the plane of the flanges in which they are formed, said ears being provided with holes 19 and 19' respectively 80
- 20 of a size to permit a dowel pin 9 to pass therethrough. The distance between these ears or extensions are the same as those between the dowel pins 9 of the side walls of the cabinet structure. 85
- 25 The vertical connecting webs 16 and 16' may be respectively provided with suitable countersunk screw holes 20, 20' for the passage therethrough of the screws 21 and the lower flanges 17, 17' are also provided with 90
- 30 holes 22 and 23 and 22' and 23' respectively for the passage of bolts therethrough. The ends of the lower flanges 17 and 17' opposite to those which are provided with holes 22, 23 and 22' and 23' are preferably 95
- 35 respectively provided with tapped holes 24 and 24' for the reception of a screw. A pair of these Z-bars are used in carrying out our invention, and they are similar in construction except that they are complementary, i. e., 100
- 40 right and left, and except that the bar 15 which is to be attached to, for instance, the right hand wall 4 of the cabinet, may be provided with a notch or cut away portion 105
- 45 for the passage therethrough of the usual pivoted bar (not shown) operative to hold the lid 26 of the talking machine structure in elevated position by the engagement thereof with the usual lid supporting plate 27. The 110
- 50 holes in the lower flange 17 of one Z-bar are complementarily arranged with respect to the similar holes in the lower flange 17' of the complementary Z-bar 15'; that is to say, when the bars are arranged with their connecting webs vertical and their lower flanges 115
- 55 extending toward each other, the threaded holes or tapped holes 24 and 24' will be opposite each other and the cylindrical holes 22 and 23 will be opposite the cylindrical holes 22' and 23'. 120
- 60 The lengths of these Z-bars are substantially the same as the depth of the inside of the cabinet, that is to say, they are as long as the distance between the inner faces of the front and back walls 1 and 2 respectively. 125
- 65 These Z-bars are preferably built into the cabinet construction before the strips 5, 6, 7 and 8 are attached to the tops of the main portions of the walls 1, 2, 3 and 4 respectively. The upper flanges 14, 14' of the Z-bars 15 and 15' respectively are snugly 70
- 75 fitted into the grooves 10 and 11 in the opposite side-walls with the holes 19, 19' respectively in alignment with the holes 4 of the dowel pins 9. When so positioned the upper strips 5, 6, 7 and 8, are rigidly glued 75
- 80 to the top walls 1, 2, 3 and 4 respectively of the cabinet, with the dowel pins 9 passing through the holes 19 and 19' and the webs 16, 16' resting respectively against the inner faces of the side walls 3 and 4. Screws 21 80
- 85 are then preferably driven into the inner face of the side walls through the holes 20, 20' in the webs 16, 16'. 85
- 90 When assembled in this manner the lower flanges 17 and 17' of the Z-bars 15 and 15' respectively extend outwardly from the inner faces of the side walls and inwardly horizontally with respect to the cabinet, said flanges being disposed in the same plane and extending toward each other forming 90
- 95 ledges or seats upon which are respectively supported the ends of the motor-board 28 and the horn-board 29. 95
- 100 The board 29 is termed the "horn-board" for brevity and convenience. It is the board 95
- 105 from the lower side of which the horn bracket 30 usually depends, said horn bracket terminating in a suitable horn or amplifier 31 having its mouth adjacent an opening 32 in the front wall 1 of the cabinet, but this "horn-board" may, and preferably does also support on its upper face a bracket 33 upon which is mounted to swing the usual tone arm 34, said bracket 33 and horn bracket 30 being preferably rigidly secured 100
- 110 to opposite sides of said horn-board 29 by bolts or screws 35. The front edge 36 of the horn-board 29 is preferably beveled to provide an overhanging portion or overhanging wall, as clearly shown in Fig. 2, and the said horn-board is provided preferably near the four corners thereof with holes which register with the holes 22, 23 and 22' and 23' respectively in the lower flanges 17 and 17' 110
- 115 of the Z-bars 15 and 15', nuts 38 serving to firmly but removably hold the ends of the horn-board 29 on the seats or ledges provided by the inwardly extending flanges 17 and 17' of the Z-bars 15 and 15' respectively. The ends of the horn-board 29 preferably 115
- 120 abut firmly against the inner sides of the webs 16, 16' respectively, and the rear edge 39 preferably fits snugly against the inner face of the rear wall 2. 120
- 125 The motor-board 28 is also of a size and shape to preferably snugly fit into the space between the opposite webs 16 and 16' of the Z-bars and between the inner face of the front wall 1 and the overhanging front edge 36 of the horn-board 29. The rear edge 40 130

of the motor-board 28 is preferably beveled so that it fits under and against the overhanging front edge 36 of the horn-board 29 and the corners of the motor-board 28 remote from the front edges 36 of the horn-board 29 are provided with openings which register with the threaded or tapped openings 24, 24' near the front ends of the lower flanges 17, 17' of the Z-bars 15, 15' respectively and through these openings and into the threaded holes 24, 24' are preferably threaded machine screws 41 by means of which the front corners or the front edge of the motor-board 28 is rigidly but removably secured to the Z-bars 15, 15'.

In either arrangement, however, the weight carried by the motor-board, and that carried by the horn-board will be directly supported by the vertical side walls of the cabinet 20 through the stiff metallic Z-bars, the upper flanges of which rest throughout their length on the bottom surface of the grooves in the side walls. The screws 29 do not support any substantial part of the said weight. They 25 merely hold the webs flat against the side walls, hold the upper flanges from displacement out of the grooves when the said boards are removed, and make the stiff Z-bars unitary with the cabinet walls to which they are 30 attached.

The horn-board and the motor-board are as long as the width of the inside of the cabinet measured between the webs of the Z-bars and the combined width of said boards 35 is equal to the depth of the inside of the cabinet between the front and rear walls. These boards together then form a rigid but removable partition snugly fitting substantially against the four walls of the cabinet, 40 completely filling the space between said walls, said partition when so seated on and secured to said flanges of the Z-bars, forming virtually a substantial part of the cabinet 45 itself.

Preferably pads of felt 42 are placed on the upper faces of the flanges 17, 17' near the corners of the motor-board and of the horn-board so that between the under sides of the 50 said boards and the upper faces of the said flanges 17, 17' there are provided more or less yielding cushions or pads 42.

Depending from the motor-board, and secured thereto in any suitable manner, is a motor 43 serving to rotate the spindle 44, extending through but out of contact with the motor-board, and operative, at its upper end, to support and rotate a turntable 45 located above the motor-board 28.

In the above construction we have substantially replaced the expensive heavy built-in wooden partition commonly used to impart strength and rigidity to the upper part of a talking machine cabinet where strength is particularly required by reason of the mounting at this point in the cabinet of the heavy

motor, turntable and horn bracket, with a partition comprising two boards supported at their ends only on two metal ledges rigidly secured to the inner faces of two opposite walls of the cabinet structure and we have 70 rigidly secured these two boards to the horizontal flange of the metallic strips by screws or bolts, so that these two boards together form a partition serving to separately support the horn and motor, and also serving to 75 impart the required strength and rigidity to the upper part of the cabinet, all in such a way that the motor-board may be removed from the machine by simply unscrewing two screws in the corners thereof remote from the 80 contacting edges of the two boards, at the corners of the motor-board which are at or near the front vertical wall of the cabinet structure. By rigidly securing the horn-board at its four corners to the flanges 17 and 17' and by providing its forward edge 36 with an undercut so that that edge is an overhanging edge, and by giving a complementary shape to the rear edge 39 of the motor-board, the motor-board is firmly retained and rigidly supported on the upper flanges of the Z-bars by the overhanging edge 36 of the horn-board and the two screws 41 at their inner front corners.

While to illustrate our invention we have shown a cabinet substantially square in horizontal cross-section, our invention is not to be construed as limited strictly thereto, because in those structures of the so-called console type, the talking machine mechanism is ordinarily enclosed within four vertical walls, but the side-walls particularly, are not necessarily the out-side walls of the cabinet structure per se. They are intermediate walls arranged to enclose between them the talking machine mechanism and to provide compartments or chambers for the storage of records or for other purposes, between said intermediate side walls and the out-walls of 100 the cabinet. Such cabinets may readily be 105 provided, in the intermediate side-walls adjacent the talking machine mechanism, with our improved insert Z-bars, and the motor-board and horn-board may be readily secured thereto, in the manner above described, without departing in any way from the spirit and scope of our invention.

While we have described those flanges of the Z-bars which fit into the grooves on the opposite sides of the side walls as provided with ears and openings therethrough for the passage of dowel pins, in some constructions these ears may be omitted and engagement of the flanges with the walls of the grooves and the attachment of the webs to the inner faces of the side walls will form a support cooperating with the motor-board and the horn-board sufficient to greatly stiffen and strengthen the upper part of a talking machine structure.

A talking machine constructed and arranged in the manner above set forth appears to us to give a better and more satisfactory reproduction of sound than that obtained by a machine equipped with the old rigid built-in wall or partition. This may be because the whole partition, being supported at its ends only within the cabinet, and those ends being rigidly secured to a rigid metallic support rigidly mounted in the rigid walls of the cabinet, is free to elastically support the horn and tone arm, and to yield or vibrate in sympathy with the tones being reproduced from the record. Whether this explanation fully accounts for the improved quality of the reproduced tone, applicants are not prepared at the present time, to positively state, but a machine constructed with and embodying this invention, gives a reproduction of sound which is of a very superior quality.

Because in the construction above described, the webs of the Z-bars are interposed between the ends of the boards and the inner faces of the side walls, the length of said boards will be just enough shorter than the width of the inside of the cabinet as to provide ample clearance between the ends of said boards and the said inside faces when said boards are for any reason lifted off from the lower flanges out of the cabinet. The danger of scratching or marring said faces in removing said boards from the cabinet is thus obviated.

We prefer to make the thickness of said boards slightly less than the vertical width of the webs so that when the boards are seated on said bars, the corners of said bars where the webs are bent to form the upper flanges will be slightly above the plane of the upper surfaces of said boards. When, therefore, the Z-bars or angle irons are enameled, painted or otherwise finished to match the color of the cabinet or of the said boards, the said corners provide a bead between said boards and the adjacent walls of the cabinet, all of which adds to the attractiveness and finished appearance of the construction.

It will now be evident that the weight of the motor-board and horn-board and the heavy parts carried thereby is transmitted to the tops of the side walls, as distinguished from being transmitted thereto through brackets merely attached to the inside faces of the side walls, and is distributed throughout the length of the tops of said side walls. The weight of said parts is borne just as if the motor-board and horn-board rested on the top edges of said walls, but since said boards are within the cabinet and between the walls, and abut against said walls, the entire cabinet structure is greatly strengthened.

Having thus described our invention, what we claim and desire to protect by Letters Patent of the United States is:

1. The combination with relatively vertical walls of a talking machine cabinet, the inner faces of an opposite pair of the said walls being provided each with a relatively horizontal groove therein, of a pair of bars, substantially Z-shape in transverse cross-section, for each side wall, each bar having one of its flanges fitting into the groove in a wall, its web fitting against the inner face of said wall, and its other flange extending outwardly from said face of said wall, and a horn-board and a motor-board supported on said outwardly extending flanges.

2. The combination with four relatively vertical walls of a talking machine cabinet, the inner faces of the side walls of which are provided each with a relatively horizontal groove therein extending substantially the length thereof, of a pair of bars, substantially Z-shape in transverse cross-section, one for each side wall, each bar having its upper flange fitting into the groove of a side wall, its web fitting against the inner face of said side wall below said groove and its lower flange extending outwardly from said face of said side wall, and a horn-board and a motor-board supported at their ends on said outwardly extending flanges.

3. The combination with four relatively vertical walls of a talking machine cabinet, the inner faces of the side walls of which are provided each with a relatively horizontal groove therein extending substantially the length thereof, of a pair of bars substantially Z-shape in transverse cross-section, one for each side wall, each bar having its upper flange fitting into the groove of a side wall, its web fitting against the inner faces of said side wall below said groove, and the lower flange extending outwardly horizontally from said face of said side wall, a horn-board supported at its ends on said lower flanges of said Z-bars and having an overhanging front edge, a motor-board also supported at its ends on said lower flanges and having its rear edge fitting against and under said overhanging edge of said horn-board, means for securing said horn-board to said lower flanges, and means for removably securing the two front corners of said motor-board to said lower flanges.

4. The combination with four relatively vertical walls of a talking machine cabinet, the inner faces of the side walls of which are provided with a ledge extending outwardly from said side walls and toward each other, the upper surfaces of said ledges being in a relatively horizontal plane, of a horn-board supported at its ends on said

- upper surfaces of said ledges and having an overhanging front edge, a motor-board also supported at its ends on said upper surfaces of said ledges and having its rear edge fitting against and under the overhanging edge of said horn-board, means for rigidly securing said horn-board to said ledges, and means for removably securing said motor-board to said ledges at points 5 relatively near the front corners of said motor-board.
5. The combination with relatively vertical walls of a talking machine cabinet, the inner sides of a pair of opposite walls of which are provided each with a relatively horizontal groove extending substantially the length thereof, of a pair of metallic bars, one for each of said opposite walls, each bar having one free edge fitted respectively into 10 the groove of one of said opposite walls and its other free edge extending outwardly horizontally from said wall, whereby a pair of inwardly extending ledges is formed on said opposite side walls, a horn-board supported 15 at its ends on said ledges, a motor-board also supported at its ends on said ledges, and means for rigidly removably securing said boards to said ledges.
6. The combination with relatively vertical walls of a talking machine cabinet, the inner sides of a pair of opposite walls of which are provided each with a relatively horizontal groove extending substantially the length thereof, of a pair of metallic bars, one for 20 each of said opposite walls, each bar having one free edge fitted into the groove in one of said opposite walls respectively, and provided with holes therethrough near said edge, pins in said wall passing through said 25 holes to permanently lock said bar in said groove, the other free edge of said bar extending outwardly horizontally from said wall, whereby a pair of inwardly extending ledges is formed on said opposite side walls, a horn-board supported at its ends on said 30 ledges, a motor-board also supported at its ends on said ledges, and means for rigidly removably securing said boards to said ledges.
7. The combination with four relatively vertical walls of a talking machine cabinet, the inner faces of a pair of opposite walls of which are provided each with a relatively horizontal groove extending substantially the length thereof, of a pair of bars, one for 35 each of said opposite side walls, each bar having one free edge fitted respectively into the groove of one of said opposite walls and its other edge extending outwardly horizontally from said face of said wall whereby a pair of inwardly extending ledges is formed on said inner faces of said opposite walls, a horn-board supported at its ends on said ledges and rigidly secured thereto 40 and having an overhanging beveled edge, a

motor-board also supported at its ends on said ledges and having a longitudinal edge beveled to fit against said overhanging edge of said horn-board, and means to rigidly and removably secure said motor-board to 70 said ledges at points remote from said beveled edge, said horn-board and said motor-board together forming a partition substantially filling the space between said four vertical walls of said cabinet. 75

8. In a talking machine cabinet the combination with two relatively vertical opposite walls, the tops of which comprise separate strips permanently secured to the main portions of said walls and pins connecting said strips with said main portions of said walls, an inner horizontal groove being provided in the inner faces of said walls where said strips join the main portion of said walls, of a pair of bars, substantially Z-shape in 80 transverse cross-section, each having one of its flanges fitted into a groove in one of said walls respectively, its web lying flat against said wall and its other flange extending outwardly therefrom to form relatively horizontal ledges on each of said walls, and a partition supported on said ledges and removably, fixedly secured thereto. 85

9. In a talking machine cabinet, the combination with two relatively vertical opposite walls, the tops of which comprise separate strips permanently secured to the main portions of said walls and dowel pins extending between and into said strips and said main portions of said walls, a narrow 95 groove being provided in the inner face of said walls where said strips join the main portions of said walls, said groove extending around said dowel pins, a pair of metal bars, substantially Z-shape in transverse 100 cross-section, each having its upper flange fitted respectively into a groove of one of said walls, its web lying flat against said wall and its lower flange extending outwardly therefrom to form a ledge on said wall, the upper flanges of said bars being 105 also provided with openings through which pass said dowel pins, and a partition supported at its ends only on said ledges and rigidly and removably secured thereto. 110

10. In a talking machine cabinet having four relatively vertical walls comprising a front wall, a rear wall and two opposite side walls, the combination of a pair of metallic bars, Z-shape in transverse cross-section, each bar being secured respectively to one of said side walls with the intermediate web thereof flat against the inner face of said side wall, one flange projecting outwardly therefrom, whereby are formed opposite parallel ledges disposed in the same horizontal plane and extending inwardly toward each other, a horn-board and a motor-board having their opposite ends supported on said ledges respectively and their ends fitting 115

against and between the webs of said pair of bars, and means for removably fastening said boards to said ledges whereby when said boards are lifted out of said cabinet 5 the ends thereof are out of contact with the inner faces of said vertical side walls.

11. In a talking machine cabinet comprising two opposite walls, the combination of a pair of metallic bars, Z-shape in transverse cross-section, each secured respectively to one of said side walls with the intermediate web thereof flat against the inner face of a side wall and one flange projecting outwardly therefrom to form ledges projecting 15 inwardly toward each other arranged in the same plane, a partition supported on and secured at its opposite ends respectively to said ledges, the top surface of said partition being slightly below the upper edges of said 20 webs.

12. In a talking machine cabinet comprising two opposite walls, having respectively a groove in their inner faces, the combination of a pair of metallic bars, Z-shape 25 in transverse cross-section, each having a flange firmly seated in the groove in one of said walls respectively, a web flat against said wall, and a flange projecting outwardly from said wall whereby are formed on said 30 opposite walls, ledges projecting inwardly towards each other, a partition seated on said ledges, and fitting between the webs of said bars, and means to rigidly removably secure said partition to said bars.

13. In a talking machine cabinet comprising four vertical walls, two opposite walls of which are respectively provided with a substantially horizontal groove in the inner faces thereof, the combination of 40 a pair of metallic bars Z-shape in transverse cross-section, each having a flange firmly seated in the groove in one of said walls respectively, a web flat against said wall, and a flange projecting outwardly 45 from said wall, whereby are formed on said opposite walls, ledges projecting inwardly towards each other, a substantially rectangular partition seated on said ledges and having two opposite edges snugly fitting between and abutting against the webs respectively of said Z-bars and its other opposite edges snugly fitting between and abutting against the other two walls respectively of the cabinet, and means to rigidly secure said 50 partition to said bars.

14. The combination with four relatively vertical walls of a cabinet structure, an opposite pair of which walls are provided each with a relatively horizontal groove in the 55 inner faces thereof, of a pair of metal bars, substantially Z-shape in transverse cross-section, each secured to the face of said opposite walls respectively with one flange fitting in the groove of a wall, with the other flange extending outwardly horizontally

from said wall and with the intermediate web flat against said wall, a pair of boards supported at their ends only on said outwardly extending flanges, disposed side by side and in edge contact with each other, 70 and substantially filling the space between said webs and between the other two walls of said cabinet, one of the engaging edges of said boards being under-cut to provide an overhanging portion, and the adjacent edge of the other of said boards being shaped to fit against and under said overhanging edge, means to rigidly removably secure four corners of the said board having the overhanging edge to said supporting flanges, and means to rigidly removably secure said other board to said flanges, and at the two corners thereof which are remote from the said engaging edges of said 75 boards.

15. The combination with four relatively vertical walls of a cabinet structure, of a pair of ledges extending from two opposite walls, the upper surfaces of which lie in the same relatively horizontal plane, of a motor-board and a horn-board supported at their ends on said ledges, said boards being arranged side by side with their adjacent edges in contact and said boards together substantially filling the space between said 90 walls and forming a partition or relatively horizontal wall, the edge of said horn-board engaging said motor-board and being arranged to overhang the adjacent edge of said motor-board, means to rigidly secure 95 said horn-board to said flanges, and means to removably and rigidly secure said motor-board to said flanges near the corners thereof remote from said horn-board, whereby said horn-board is held in place by said 100 means for attaching said corners thereof to said flanges and by the overhanging edge of said horn-board.

16. The combination with the vertical walls of a talking machine cabinet having a transverse partition therein substantially filling the space enclosed between said vertical walls, the inner sides of two opposite vertical walls being provided each with a groove extending transversely thereto substantially the length thereof, of a pair of angle-irons or bars each substantially Z-shape in transverse cross-section having parallel flanges connected by a vertical web, the upper flanges of said bars being respectively fitted and held in said grooves, the webs of said bars lying respectively against the inner faces of said opposite walls and the lower flanges of said bars forming ledges upon which rest the opposite edges of said 115 partition.

17. The combination with the relatively vertical walls of a talking machine cabinet, the inner side of opposite side walls of which is provided with a groove, of a pair of angle- 120 125 130

irons each substantially Z-shape in cross-section, one for each side wall, each angle-iron respectively having its upper flange seated in one of said grooves and being provided with an opening therethrough, its web fitting against the inner side of the wall and its lower flange extending outwardly from said wall, means for fastening said webs firmly to said side walls, pins in said side

walls extending through said openings in 10 said upper flanges, and a partition seated on and rigidly secured to said lower flanges, and having its edges fitting snugly against said walls.

In witness whereof, we have hereunto set our hands this 20th day of October, 1922.

EUGENE T. KIEFFER.
WILLIAM B. STEVENSON.
